UNITED STATES PATENT OFFICE.

JOHN OWENS, OF KINGSTON, IOWA.

GASOLENE-LAMP.

1,238,562.

Specification of Letters Patent. Patented Aug. 28, 1917.

Application filed February 7, 1917. Serial No. 147,088.

To all whom it may concern:

Be it known that I, JOHN OWENS, a citizen of the United States, and a resident of Kingston, in the county of Des Moines and 5 State of Iowa, have invented a certain new and useful Improvement in Gasolene-Lamps, of which the following is a specification.

My present invention relates generally to gasolene lamps, and more particularly to a 10 certain construction thereof adjacent the burner, and utilized in connection with either gravity feed or force feed gasolene lighting systems.

The primary object of my present improvements is to provide a gasolene lamp including operating parts of the utmost simplicity, the construction and use of which 15 enables the production of an inexpensive lamp of this type, both as to first cost and 20 upkeep, the several parts comprising my improvements as hereinafter specified being such as to not only permit of ready and inexpensive insulation of the lamp in the first instance, but detachment, repair, or substitution of any one or more of such parts in a 25 ready, quick, and inexpensive manner, without the necessity of skilled labor, or the use of special tools and implements for this purpose.

As is well known, the successful gasolene lamps now in use are of a complicated, expensive construction, such that, when the parts thereof become worn, broken, or disarranged, it is generally necessary for the 30 user to purchase an entirely new lamp, the expense of repair by skilled mechanics such as required in these cases, being so great as to be somewhat in the nature of false economy.

With my present improvements, however, a gasolene lamp may be produced including a minimum number of parts, all of which are of simple construction, free from complication, and of inexpensive nature, which 35 may be readily removed for repair and substitution, and which will permit the owner, without especial skill, to substitute or repair parts.

In the accompanying drawings illustrating my present improvements:

Figure 1 is an elevation, partly broken away and in section, of a hanging type of lamp embodying my improvements;

Fig. 2 is an enlarged vertical section 55 through certain parts thereof;

Fig. 3 is a detail horizontal section taken substantially on line 3—3 of Fig. 2;

Fig. 4 is an elevation showing my improvements as applied to a bracket type of lamp, and illustrating a slightly modified 60 form;

Fig. 5 is an enlarged view of a portion of Fig. 4, partly broken away and in section;

Fig. 6 is a view similar to Fig. 5, illustrating another slight modification, and 65

Fig. 7 is a detail horizontal section taken substantially on line 7—7 of Fig. 5.

Referring now to these figures, and particularly to Figs. 1 to 3 inclusive, I have shown a lamp including a hanging frame 10 provided at its lower central portion with a flattened section 11, and downwardly along one side of the hanging frame 10 is extended a gasolene feed pipe 12.

My improvements contemplate the use of 75 an upright tubular gas feeding member 13 having a pair of laterally projecting oppositely disposed side ears 14, provided with openings aligned with openings of the flattened section 11 of the frame 10, for the 80 reception of screws 15 or like fastening members whereby to detachably connect the gas feeding member 13 upon the frame 10.

By reference to Fig. 2 it will be noted that the upper portion 16 of the bore of the 85 tubular member 13 is of less diameter than the lower portion 17 of said bore, a valve seat 18 being formed at an intermediate point, and the lower end of the bore 17 being closed by a threaded plug 19.

Seated in a conical cavity at the upper 90 end of the upper portion 16 of the bore, is a conical spray plug 20, the upper outer portion of which is shouldered for engagement by a clamping ring 21 threaded upon the upper end of the member 13, the latter of which is provided at its lower end with a laterally projecting nipple 22 communicating with the bore 17, said nipple being also provided with a conical cavity, for the 95 reception of the conical head 23 and the adjacent end of the gasolene feed pipe, held securely within the conical cavity by a clamping ring 24 threaded upon the nipple 22.

Upwardly through the plug 19 is threaded 100 a stem 25 having a valve 26 adjacent its upper end, for engagement with the valve seat 18, and having an upwardly projecting reduced extension 27 extending upwardly into the upper portion 16 of the bore, with a nee- 105

dle 28 at its upper extremity adapted for passage through the reduced opening of the spray plug 20 when the valve 26 is moved to closed position against the valve seat 18, the stem 25 being manipulated by means of a key or other form of handle 29 upon its lower external end.

By referring again to Fig. 1, it will be noted that the upper end of the member 13 receives the burner pipe 30, loosely disposed thereon in telescoping relation, and thus wholly supported by the member 13, the burner pipe 30 having a laterally opening air intake 31 and having depending burner supports 32 for the reception of the usual mantle, extending downwardly alongside the member 13, so that the heat from the burners in use will provide the necessary heat within the member 13 for the generation of gas from the liquid gasoline fed thereto through the pipe 12 and nipple 22 and regulated by the valve 26, the spray plugs 20 opening within the burner 30, as seen by reference to Fig. 2.

It will thus be understood that with my improvements as described, the generation of gas takes place within the member 13, the latter acting as a generator, and the stem 25 acts both as a regulating valve and as a spray plug cleaner.

In the form of the invention shown in Fig. 4, the gas feeding member 33 is secured in the same manner as above described, to the flattened portion 34 of a side wall or other bracket 35, along which the gasoline feed pipe 36 extends, the latter being similarly connected to a nipple 37 of the member 33. The burner pipe 30 is of the same construction in this figure as in the form shown in Figs. 1 and 3, and, in fact, the other forms to be presently described, and is supported and acts in the same manner. In the form shown in Fig. 4, however, the threaded stem 38 acts as a spray plug cleaner 45 alone, a regulating valve 39 being threaded laterally into the lower portion of the member 33 in this figure, as well as in Figs. 5 and 7, with an inner valve 40 co-operating with a valve seat 41 adjacent the nipple 37 50 in a plane at one side of the plane of the stem 38, as clearly seen by reference to Fig. 7.

In Fig. 4 the member 33 acts as a generator as in Figs. 1 to 3 inclusive, but in accordance with the form shown in Fig. 5, a small generator tube 42 may be utilized with headed conical ends 43 secured to nipples 44 extending laterally from the member 45 at vertically spaced points, so that the generation takes place more particularly in the generator tube 42, gasoline passing thereto at its lower end and gas passing from its upper end back into the upper portion of the bore of the member 45.

The same construction as regards the gen-

erator tube 42 of Fig. 5 is present in the form shown in Fig. 6, where the vertical stem 46 has an intermediate valve 47 co-operating with a valve seat 48, in addition to its plug cleaning needle extension 49 so that the stem performs the double function of a regulating valve and plug cleaner as described in connection with the form shown in Figs. 1 to 3. The gas feeding member 50 of Fig. 6, with its lower nipple 51 receiving the gasoline feed pipe 52, is otherwise the same as described in connection with Fig. 5, and is to be secured upon the flattened portion of either a hanging frame, as in Fig. 1, or a bracket as in Fig. 4, the same as the corresponding gas member in the several other figures.

It is obvious that, in this way, I provide an arrangement including a minimum number of parts, particularly in connection with the most simple of the forms, as illustrated in Figs. 1 to 3, wherein the gas feeding member may be readily and quickly detached as well from the supporting frame as all the other parts, in order that repair thereof, or substitution of either one of its parts, for instance the spray plug 20, or substitution of an entirely new gas feeding member, may be readily and quickly effected without the use of special tools for the purpose or without requiring especial skill in the operation.

I claim:

1. In a gasoline lamp, the combination of a support having a seat portion and a gasoline feed pipe, a gas feeding member to which the feed pipe is connected extending above the seat portion of the support and having lower external connecting means detachably secured to the said seat portion of the support, a regulating valve within said member, and a burner pipe removably disposed and supported upon the gas feeding member and into which the upper end of the latter opens, said burner pipe having depending burner supports extending alongside the gas feeding member, for the purpose described.

2. In a gasoline lamp, the combination with a support having a flattened portion and a gasoline feed pipe, of an upright tubular gas feeding member to which the feed pipe is connected, having lower external side lugs, fastening means detachably connecting said lugs to the said flattened portion of the support, and a burner pipe disposed on and supported by the upper end of said member and having burner supports depending alongside the said member.

3. In a gasoline lamp, the combination with a support and a gasoline feed pipe, of a tubular upright gas feeding member to which the gasoline feed pipe is detachably connected, means for detachably connecting the said upright member to the said support,

a generator tube carried by the said member and communicating at its opposite ends with the bore of said member at vertically spaced points, and a burner pipe detachably supported upon the upper end of said member and having burner supports depending alongside the said member.

4. In a gasolene lamp, the combination with a support, and a gasolene feed pipe, of a gas feeding member detachably con-

nected to the support and to which the pipe is attached, said member having laterally projecting nipples at vertically spaced points, a generator tube supported by the said member and connected at its opposite ends to the said nipples, and a burner pipe supported upon the upper end of said member and having burner supports depending alongside the said member.

JOHN OWENS.
